Primary Examiner — Thomas Johannes*Assistant Examiner* — Catherine Posthauer(74) Attorney, Agent, or Firm — Christie, Parker & Hale, LLP(57) CLAIM

The ornamental design for a seated easel, as shown and described.

DESCRIPTION

FIG. 1 is a perspective view of the seated easel;

FIG. 2 is a right side view thereof;

FIG. 3 is a left side view thereof;

FIG. 4 is a front view thereof;

FIG. 5 is a back view thereof;

FIG. 6 is a top view thereof; and,

FIG. 7 is a bottom view thereof.

The broken lines are shown for the purpose of illustrating portions of the seated easel and form no part of the claimed design.
